YARN CONDITIONING MEANS FOR
KNITTING MACHINES

Henry Janssen, Wyomissing, Pa., assignor to
Textile Machine Works, Wyomissing, Pa., a
corporation of Pennsylvania

Application December 4, 1935, Serial No. 52,752

8 Claims. (Cl. 66—125)

My invention relates to means for conditioning the yarn employed in a knitting machine, and particularly to means for preparing the yarn for effective manipulation by the knitting mechanism 5 of a straight, or full fashioned, knitting machine,

In knitting sheer fabrics of fine yarns, such as silk stockings, factors such as temperature and air current conditions, stoppages of the machine, the distance traveled from the yarn supply to the knitting mechanism, and the time required for the yarn to travel this distance, must be taken into consideration.

As shown in my copending application, Serial No. 13,858, filed March 30, 1935, for the Method 15 of, and means for, effecting vapor treatment of yarn in a yarn fabricating machine, some of these factors are taken into consideration so as to render the treatment or conditioning of the yarn, in its stated use, a definite improvement over 20 methods and devices heretofore employed.

In the invention of the copending application, the quantity, temperature and kind of moisture are not only so provided and controlled to materially improve the fabric, and its production, but 25 all of the yarns of an entire machine of several sections are so uniformly conditioned, as to avoid the further objection of differences in the fabrics produced by such machine, this factor also apparently being first recognized and overcome by 30 the invention of the said copending application.

However, in the device of that application, the 35 yarns subjected to the improved treatment as stated, are only the yarns on the packages, or cones, and lengths of these yarns extending from the packages for relatively short distances toward the feeding, tensioning and knitting mechanisms, in which lengths the tension of the yarns is not under definite control, this feature resulting from certain standard practices in the 40 design of the knitting machine, in view of which the invention was applied in the most effective manner apparent. In other words, by reason of certain space factors, complication and location of the many parts of a full fashioned knitting 45 machine, the invention of the copending application was applied in as effective manner as was presented, without substantial change of the machine design, and without the injection of the novel features and construction of the present 50 invention.

It is an object of this invention to make use of the heretofore apparently unknown expedient of not only enclosing the yarn packages and certain lengths of the yarns extending from the 55 packages, whereby to subject the yarns to con-

fined moist air, but also to enclose certain working parts of the knitting machine itself, which although subjecting these parts to the moisture, which is compensated for by means in accordance with the invention, provides the substantial added 5 advantages of greatly increasing the length of yarn that can be maintained in effective knitting condition, reduces the extent of exposure of the yarn after having been conditioned and passed to the knitting parts, and provides other ad- 10 vantages. This result is also obtained without substantial change in a standard machine.

Another object of the invention is to treat portions of the yarn while these portions are either 15 relaxed or under tension, are successively under each of these conditions, or successive lengths of the yarn are simultaneously relaxed and tensioned, respectively, whereby a greater variety of conditions, and increased flexibility in the choice of conditions, are obtained.

Another object is to not only more effectively condition a single yarn, and to subject all the 20 yarns of any given group, which should be so subjected, to simultaneous, or like, treatment, as in the invention of the copending application, but 25 also to do so over a greater length of the yarn or yarns, and to so treat all of the yarns for a greater period of time.

Another object is to maintain the condition of the yarn, effected as above set forth, to a point 30 as close to its entry into the loop-forming mechanism, as the structure of the machine will permit, which is different in different machines, and in different parts of the same machine, to the end that the yarn of the supply to the mechanism is 35 maintained in the improved condition substantially throughout its length.

Another object of the invention is to provide a 40 structure for effecting the above-mentioned objects that shall be simple and durable in construction, economical to manufacture and effective in its operation.

With these and other objects in view, which will 45 become apparent from the following description of the illustrative embodiment of the invention 45 shown in the accompanying drawings, my invention resides in the novel method, elements, features of construction and arrangement of parts in cooperative relationship, as hereinafter more particularly pointed out in the claims.

In the drawings:

Figure 1 is an outline view, in rear elevation, of a multi-section full-fashioned knitting machine embodying a yarn-conditioning device of my invention;

Fig. 2 is an enlarged top plan view of a portion of the machine between the arrows 2—2, of Fig. 1, parts being broken away;

Fig. 3 is an enlarged transverse vertical sectional view of a portion of the device taken substantially along the line 3—3 of Fig. 1;

Fig. 4 is an enlarged view of a portion of the device as viewed in Fig. 1, but in section to show the interior thereof.

Fig. 5 is a detail perspective view of a portion, or removable intermediate section, of a yarn receptacle indicated in the other figures; and

Fig. 6 is a perspective view of the closed end of one of the end sections of the yarn receptacle.

Referring to the drawings, the illustrative example of the invention is shown as applied to a "Reading" full fashioned knitting machine, only the parts of which, necessary to an understanding of the invention, are shown, the other parts and the operation thereof being well known, as shown and described in the "Reading" Full Fashioned Knitting Machine Catalogue, copyright 1929, and published by the Textile Machine Works, Reading, Pennsylvania.

As better seen in Figs. 1 and 3, a multi-section full fashioned knitting machine includes frames 12, a back beam 15, a front bed 18, a center bed 19, a bank of needles 22, secured to a needle bar 24 by clamps 25, a sinker-head assembly S, carrier rods 1—8 longitudinally reciprocably mounted on brackets 27 on the center bed 19, yarn-carrier fingers 29 secured to the carrier rods, a needle presser lever 32 for operation by a usual cam and cam shaft assembly, not shown, a rear support bar 35 connected between the frames 12, and a coulier-motion mechanism C, the above-mentioned parts all being as heretofore employed.

Other parts, as seen in Fig. 3, are also of usual character, location and operation, but are supported and affected in novel manner in accordance with the invention, as will herein appear.

Referring to Fig. 1, between each pair of frames 12, there are two complete knitting mechanisms 45 of the kind indicated in Fig. 3, each for knitting a stocking blank, and, also for each two knitting mechanisms so disposed there is one section of a unitary receptacle A extending substantially throughout the length of the machine, the sections of the receptacle A being end sections 37 and sections 38 between the end sections 37. Each intermediate section 38, before assembly with the other sections, is open at each end, as indicated in Fig. 5, and each end section 37, as seen in Fig. 6, before assembly on the machine, is closed by a wall 39 at its end farthest from the next adjacent intermediate section 38 and open at its end next to such section, so that, although the sections may be individually taken apart and removed from the machine for repair or other purposes, when they are assembled, as shown in Fig. 1, they constitute only one receptacle in which all of the yarns are disposed.

At the ends of the receptacle A, and between the sections of the receptacle, at positions in the transverse planes of the frames 12, brackets or gallows 42 are provided for supporting the receptacle, each of these brackets, as better seen in Fig. 3, comprising an upright 43 secured at its lower end to the rear support bar 35. The upright 43 has a bottom rearwardly-projecting arm 44, a forwardly-projecting arm 47 intermediate the top and bottom of the upright, and further portions 48, 49, 52, 53, 54 and 57.

The receptacle A is of inverted substantially L-section having its upright leg enclosing package supports 58 and its transverse leg, extending forwardly from the upright leg, enclosing tensioning devices, and supported by the arm 47. Each section of the receptacle having such cross section, is therefore provided with rear, intermediate and forward walls, in the rear wall of which are upper and lower glass paneled sliding doors 59 and 62, respectively, in the intermediate wall of which are glass paneled doors 63 and, in the forward wall of which are glass paneled sliding doors 64. The structure is, in general, of sheet metal construction, except for the glass of the doors and a pane 67 in the top wall 68, this construction being provided to admit plenty of light to, and prevent the formation of mold in, the receptacle. Removable bars 71, 72 and 73, at the rear, top and front sides of the receptacle A, provide for the more rigid support of the receptacle, and for the removal of the individual sections, while other sections are retained in position.

A yarn package 74 on one of the supports 58 supplies yarn 75 through an eye 76 on the bracket portion 49, over a guide 77 on the bracket portion 52, through a moistening trough 78, through a tension ring 79, through a snapper X, through an eye 82 in a sheet metal portion 83 of the receptacle and along a groove in the yarn carrier finger 29 on the carrier rod 5. Similarly, a yarn package 84 supplies yarn 85 through an eye 86, over a guide 87, through the moistening trough 78, through a tension ring 88, through a snapper Y, through an eye 89, and along a groove in the yarn carrier finger 29 on the carrier rod 8; these relations being merely by way of example, as there is actually a yarn package similarly, or otherwise, related to each yarn carrier finger of each knitting section. The tension rings 79 and 88 are vertically loosely movable on guides 90 secured to and depending from the gallows bracket arm or portion 57, in accordance with usual practice. The moistening trough 78 is also supported by a usual hanger or hook like support 91 embracing a bar 92 connected to, and spanning the spaces between, the gallows 43.

Each of the snappers X and Y mounted on shafts 93, see Figs. 2 and 3, comprises a body clamped to the shaft having arms 94 and 95, through openings in which the yarn 85 or 75 is adapted to pass at right angles to the shaft; the yarn passing through an eyelet in the arm 94 below its upper end, and downwardly through an opening in the arm 95. A thin leaf spring 96 is fixed at one end to the arm 94, from which it extends to a position over the arm 95, and beyond this position to a location over a stationary bar 97 mounted on the bracket portion 54.

Normally, during the stroke of the corresponding yarn carrier finger 29 the snapper parts are in such position that the spring 96 is held by the bar 97 off the yarn extending downwardly through the arm 95, so that the yarn passes freely through the snapper. During the narrowing operations 65 and at the ends of the carrier strokes, the snappers are operated by a usual camming action to turn the snappers clockwise, see Fig. 3, by a slight amount so that, when the forward ends of the springs 96 are lifted off the bars 97, these springs 70 clamp against the yarn in the arms 95 to prevent feed thereof and to move the yarn bodily backwardly for a short distance. Thus, although the yarn between the snappers or tensioning means and the packages 74 and 84 may be of varied 75

tension, the yarn from the snappers to the loop-forming mechanism is maintained under a proper and definite preselected tension.

A mechanical humidifier unit H, fully shown and described in my above-mentioned copending application, is connected by conduits 98, 99 and 102 to nozzles 104, Fig. 4, preferably provided one for each section of the receptacle A, and supplies a completely vaporized medium, at a constant relatively warm temperature and at a rate preferably automatically controlled in accordance with the rate of feed or other requirements of the yarn to the receptacle. By the uniform diffusion of the vaporized medium, it affects the yarn uniformly at all parts of its length and, by its mechanical control, it may be imposed against the yarn in greater or less amounts as desired, thus providing a much greater flexibility in the control of the conditions of the yarn than where it is left to the natural or inherent vapor tendency of stationary pools.

Also, in the device of the copending application, and in any other device of which I am aware, there has never heretofore been a moistening receptacle, corresponding to the receptacle A and employing either mechanical or static pool vaporization, that has, in effect, been any larger, or has followed the yarn, any farther from the package, than a device corresponding in size to the lower left-hand third of the receptacle A, as viewed in Fig. 3. In other words, any device of which I am aware, including, my copending application above mentioned, has heretofore only comprised a moistening box or receptacle having a cross-section corresponding to the small rectangular area immediately surrounding the packages 14 and 84, and defined or surrounded by, the parts 43, 44, 62 and 48. This area does not include, and has not in any prior device included, any of the definitely tensioned yarn or any of the working parts of the machine; whereby this yarn and its supply or package are subjected to the same conditioning medium.

By this invention, the receptacle A corresponds, in effect, to a receptacle of former construction, with an extension for enclosing a greater length of the yarn on its way from the package to the knitting mechanism.

Also, by the invention, both relaxed and tensioned parts of the yarn are subjected to vapor treatment, whereby the yarn receives the benefit of being so treated in both relaxed and tensioned conditions, it being believed that, in the relaxed condition, with the fibers more openly related, the penetration of the vapor is better, and that, in the tensioned condition, the straightening effect on the yarn is better. The results include the prevention of crinkling, which renders difficult the laying of the yarn to the many small and accurately related sinkers, dividers and needles, with its consequent sleaziness, or horizontal streak effects in the fabric, and the avoidance, in high twist yarns, of having these yarns spring out of the guide grooves in the carrier fingers, with consequent breakage of the yarn.

Although, by the arrangement, certain working parts of the machine are also subjected to the vapor, if the latter has a deleterious effect on the parts as usually constructed, the latter may either be coated, or constructed of different material to offset this effect.

It is further, in general, the purpose to extend the vapor treatment from the packages and along the yarn to as near to the carrier fingers as may feasibly be done without the sacrifice of effective

operation or other desirable features, as in the example illustrated, whereby, although the receptacle may be constructed to cover a still greater length of the yarn, such as including a further portion thereof between the eyelets 82 and 89 and the carrier fingers, this has not been done, in this example in order that access may be had to the yarn packages from the part of the machine by moving the door 63. The door 64 provides access to the snappers and other parts, and the rear doors 62 and 59, respectively, provide access to the packages and to yarn-guide parts.

Of course, the improvements specifically shown and described, by which the above-described results are obtained, may be modified in various ways, without departing from the scope of the invention as set forth herein, and in the appended claims.

I claim:

1. In a knitting machine, a yarn-supply support, knitting mechanism, mechanism for feeding yarn from the supply to the knitting mechanism, and means for conditioning the yarn for manipulation by the knitting mechanism comprising a receptacle including a portion for locally enclosing the supply and having an extension from said portion in the form of a branch arm of the receptacle for enclosing a length of the yarn on its way to the knitting mechanism, and means for conditioning the yarn in said portion and in said extension.

2. In a straight knitting machine, a yarn-supply support at the rear, between the upper and lower limits of the machine, knitting mechanism forwardly of said support, feeding and tensioning mechanism for guiding the yarn from the supply through a length extending upwardly from the supply, a length extending from said upwardly-extending length forwardly of the machine, and a length extending from said forward length downwardly to the knitting mechanism, and means for conditioning the yarn for manipulation by the knitting mechanism comprising a receptacle having a main body guard for enclosing the supply and extending along the yarn upwardly throughout said upward length, and a branch arm of the body portion extending along at least a portion of said forward length.

3. In a straight knitting machine, a yarn-supply support at the rear, between the upper and lower limits of the machine, knitting mechanism forwardly of said support, feeding and tensioning mechanism for guiding the yarn from the supply through a length extending upwardly from the supply, a length extending from said upwardly-extending length forwardly of the machine, and a length extending from said forward length downwardly to the knitting mechanism, and means for conditioning the yarn for manipulation by the knitting mechanism comprising a receptacle having a main body guard for enclosing the supply and extending along the yarn upwardly throughout said upward length, and a branch arm of the body portion extending forwardly throughout said forward length, and along at least a portion of said downward length.

4. In a straight knitting machine, a yarn-supply support at the rear of the machine, knitting mechanism forwardly of the yarn-supply support, yarn tensioning means between the yarn-supply support and the knitting mechanism, and means for conditioning the yarn for manipulation by the knitting mechanism comprising a receptacle of inverted substantially L-section having its upright leg enclosing the yarn-supply support and

its transverse leg extending from the top of said leg forwardly therefrom to enclose at least a portion of the tensioning means and of the yarn extending from the supply through the tensioning 5 means, and means for providing a yarn-conditioning medium in the receptacle.

5. In a multi-section straight knitting machine, yarn-supply supports for the respective sections at the rear of the machine, knitting mechanisms 10 forwardly of the yarn-supply supports, and means for conditioning the yarn for manipulation by the knitting mechanisms comprising a single receptacle of inverted substantially L-section having its upright leg enclosing all of the yarn-supply 15 supports and its transverse leg extending forwardly therefrom, and means for providing a yarn-conditioning medium in the receptacle.

6. In a multi-section straight knitting machine, a plurality of gallows spaced along the machine 20 each comprising an upright secured at its lower end to the machine frame at the rear of the machine, a bottom rearwardly-projecting arm and a forwardly-projecting arm intermediate the top and bottom of the upright, and a single yarn-conditioning receptacle of inverted substantially 25 L-section having its upright leg resting on all of said bottom arms and its transverse leg projecting forwardly and resting on all of said intermediate arms, and yarn guiding and tensioning

means supported by the gallows inside the receptacle.

7. In a straight knitting machine, knitting mechanism, means for supporting a yarn package at the rear of the machine, means for feeding 5 yarn from said package to said knitting mechanism, and means for conditioning the yarn for manipulation by the knitting mechanism, comprising a receptacle of inverted substantially L-section having its upright leg enclosing the package support and its transverse leg extending forwardly from said leg, the receptacle therefore 10 having rear, intermediate and forward walls, and having upper and lower doors in the rear wall, a door in the intermediate wall and a door in the 15 forward wall, and means for providing a yarn-conditioning medium in the receptacle.

8. In a knitting machine, a yarn-supply support, knitting mechanism, mechanism for feeding yarn from the supply to the knitting mechanism, 20 and means for conditioning the yarn for manipulation by the knitting mechanism comprising a receptacle including a portion for locally enclosing the supply and having an extension from said portion in the form of a branch arm of the receptacle for enclosing a length of the yarn on its way to the knitting mechanism, and means for conditioning the yarn in said portion. 25
